CLAIM

The ornamental design for a cellular telephone housing, as shown and described.

DESCRIPTION

FIG. 1 is a front, bottom, and left side perspective view of a first embodiment of a cellular telephone housing in a closed position;

FIG. 2 is a front, bottom, and left side perspective view of the first embodiment in an opened position;

FIG. 3 is a right side elevation view of the first embodiment in a closed position;

FIG. 4 is a front elevation view of the first embodiment in a closed position;

FIG. 5 is a bottom plan view of the first embodiment in a closed position;

FIG. 6 is a top plan view of the first embodiment in a closed position;

FIG. 7 is a left side elevation view of the first embodiment in a closed position;

FIG. 8 is a rear elevation view of the first embodiment in a closed position;
FIG 9 is a front, bottom, and left side perspective view of a second embodiment of a cellular telephone housing in a closed position;
FIG. 10 is a front, bottom, and left side perspective view of the second embodiment in an opened position;
FIG. 11 is a right side elevation view of the second embodiment in a closed position;
FIG. 12 is a front elevation view of the second embodiment in a closed position;
FIG. 13 is a bottom plan view of the second embodiment in a closed position;

FIG. 14 is a top plan view of the second embodiment in a closed position;
FIG. 15 is a left side elevation view of the second embodiment in a closed position; and,
FIG. 16 is a rear elevation view of the second embodiment in a closed position.
The broken line matter in all figures is for illustrative purposes only and forms no part of the claimed design.
